A. H. KLINE

PLUG CONNECTION

Filed Feb. 12, 1923

Patented July 20, 1926.

1,593,084

UNITED STATES PATENT OFFICE.

ARTHUR HENRY KLINE, OF CHICAGO, ILLINOIS.

PLUG CONNECTION.

Application filed February 12, 1923. Serial No. 618,644.

My invention relates to improvements in plug connections and it consists in the combinations, constructions, and arrangements herein described and claimed.

5 An object of my invention is to provide an improvement over that form of the device shown in my co-pending application Serial No. 412,503. In said application, I disclosed a plug in which the threaded portion is composed of two separable halves which are normally held away from each other by means of a spring. These halves are adapted to abut one another when the plug is inserted into a socket, whereby the 10 plug is yieldingly held in the socket. In the present invention, the entire plug is composed of two halves instead of merely the threaded portion being composed of two halves, which is the case in the co-pending 15 application. This construction permits the two parts of the plug to be cast in such a manner that the openings which are needed in the plug are provided when the parts are cast.

20 A further object of my invention is to provide a device of the type described in which one of the terminals also acts as a retaining means for the plug, whereby the plug is yieldingly held in the socket.

25 A further object of my invention is to provide a device of the type described in which all of the metal parts of the plug are carried by one of the members, thereby obviating the necessity of using both halves, in assembling the metal parts to the plug.

30 A further object of my invention is to provide a device of the type described in which the halves are constructed so that they may be cast in such a manner that the openings in the halves may be formed at the casting, thereby obviating the subsequent drilling of the openings after the castings are made.

35 A further object of my invention is to provide a device of the type described which is extremely simple in construction, consists of a minimum number of parts, and which can be made in the minimum number of operations.

40 Other objects and advantages will appear in the following specification, and the novel features of the invention will be particularly pointed out in the appended claims.

45 My invention is illustrated in the accompanying drawings forming part of this application, in which—

Figure 1 is a side elevation of the device,

Figure 2 is a vertical section through the device showing it operatively applied to a socket,

Figure 3 is an inside view of one half of the device,

Figure 4 is an inside view of the other half of the device,

Figure 5 is a section along the line 5—5 of Figure 3, and

Figure 6 is a section along the line 6—6 of Figure 3.

In carrying out my invention I provide a plug which is made of an insulating material, such as rubber, or any other like composition. The device consists of two halves A and B which are of the shape shown in Figures 1, 3, and 4, and which are adapted to be secured to each other by means of a screw 5. The member B is constructed so as to carry all of the metal parts of the plug while the member A is constructed to merely act as a cover for the member B. The two members when assembled resemble an ordinary plug, except that the exterior surfaces of the portions 2 and 3 of the members A and B are not threaded as is ordinarily the custom. The portions 2 and 3 of the plug are adapted to be received within the socket indicated generally at 4 in Figure 2. The member A is provided with an opening 6 through which the screw 5 is disposed, the screw being received in a threaded bore 7 in the member B. It will be noted from Figure 4 that the member A is provided with a recess 8 of the shape shown in Figure 4 and is also provided with a recess 9. The recess 8 receives the wires 10 of the plug, while the recess 9 receives a resilient terminal 11.

The member B carries terminals 11 and 12, (see Figure 3). The terminal 11 is rigidly secured to the member B by means of a rivet 13. The terminal is disposed in a portion of the recess 14. The terminal 12 is disposed in the recess 14 and is secured in place by means of a rivet 15. It will be noted from Figure 2 that the terminal 12 extends through a slot 16 and is then bent upwardly along the side of the portion 3. The portion 3 is provided with a recess 17 which receives the upwardly bent portion 18 of the terminal 12. The portion 18 has spring qualities, and is adapted to be entirely received within the recess 17.

The terminal 12 also provides novel means by which the plug is held in place in the

socket 4. The portion 18 has a cup-shaped part 19 which receives the end of a spring 20. The other end of the spring 20 is inserted in a recess 21 in the member B. It will be noted from this construction that the spring 20 yieldingly holds the portion 18 of the terminal 12 in frictional engagement with the socket 4. The cup-shaped portion 19 provides a raised portion on the exterior surface 10 of the portion 18, this raised portion being received in the threads of the socket 4. In this manner the portion 18 acts as a thread for holding the plug in the socket 4.

The other terminal 11 is curved around a projection 21' of the member B. The recess 9 is large enough to receive the terminal 11 and the projection 21'. The projection 21' prevents lateral movement of the members A and B. The screw 1 and the projection 21' 20 securely hold the members A and B together as a single unit.

The terminals 11 and 12 carry screws 22 and 23 to which the ends of the wires 10 are secured. It will be noted that this plug is especially designed so that the connection of the wires may be made to one of the members, i. e., the member B. It will also be noted that all of the metal parts are assembled to the member B and not to the member A. This results in a great saving of time in the manufacture of the device, since it is only necessary to pass the member B through the various operations by means of which the terminals 11 and 12 are assembled 35 to the member. The screws 22 and 23 are received in threaded sleeves 24 and 25 respectively, these sleeves being cast into recesses 26 and 27 of the member B.

From the foregoing description of the various parts of the device, the operation thereof may be readily understood. The electrician in wiring the plug, merely removes the screw 5, whereupon the two members are separated, thus enabling the wires 40 10 to be secured to the screws 22 and 23. The two parts A and B are now secured to each other by means of a screw 5 and the device is ready for ordinary use. As heretofore stated, the wiring of the plug is greatly simplified, since the screws 22 and 23 are fully exposed and are both on the member B.

The plug may now be inserted into any slot desired, without the necessity of rotating the plug as is usually the case. The spring portion 18 of the terminal 12 will permit the plug to be received within the socket and at the same time will yieldingly hold

the plug in place after it is once received. The free end of the terminal 11 is bent parallel with the top of the plug, and is spaced from the top. This terminal engages with the terminal (not shown) of the socket 4. When it is desired to remove the plug, it is merely necessary to pull downwardly upon the plug, whereby the portion 18 will move inwardly into the groove 17, and will permit the plug to be released from the socket 4. The device is extremely simple in construction, and consists of a minimum number of parts. The two members A and B are constructed in such a manner that the openings in the members will be made when the members are cast, thereby obviating the necessity of drilling openings in the members after the members are cast.

It will be noted that the two members A and B have recesses 28 which provide a compartment for receiving the knot 29 of the wires 10. The spring 20 not only assists in holding the plug in the socket, but also firmly holds the portion 18 in contact with the socket.

It will also be noted that the resilient terminal 11, which is spaced from the body portion B, tends to maintain a close connection with the central terminal of the socket, owing to its spring-like resiliency.

I claim:

1. A plug comprising a body portion having a smooth outer cylindrical wall, a terminal projecting from the top of said body, said body having a groove in its outer wall, a second terminal carried by said body and being adapted to be received in said groove, and a spring for yieldingly holding said terminal out of the groove, said second terminal having a cup-shaped portion for receiving the outer end of the spring, said cup-shaped portion providing a projection on the outer side of the terminal which is adapted to engage with the threads in an electric light socket.

2. A plug comprising a body portion consisting of two separate halves, said halves having faces adapted to abut each other, means for holding the halves together in abutting relation, one of said halves having a tongue therein, the other half having a groove adapted to receive the tongue, whereby a movement of the halves in the plane of their abutting faces with respect to each other is prevented and a terminal carried by said plug, said tongue also acting as a stop for said terminal.

ARTHUR HENRY KLINE.
